PROCESS FOR PURIFICATION OF
DIOLEFINSCharles E. Welling, Bartlesville, Okla., assignor
to Phillips Petroleum Company, a corporation
of Delaware

Application February 19, 1942, Serial No. 431,599

4 Claims. (Cl. 202—42)

This invention relates to the concentration of pentadienes and hexadienes from hydrocarbon mixtures containing the same together with close-boiling hydrocarbons of other types. More particularly this invention relates to the use of methyl formate to render concentration of said diolefins by fractional distillation much more practical and feasible than is fractional distillation of the hydrocarbon mixture alone.

Hydrocarbon mixtures which contain one or more diolefins with five or six carbon atoms in the molecule together with one or more other hydrocarbons of the types of mono-olefins, paraffins, naphthenes, etc., are available from various sources. One such source is the cracking, on an industrial scale, of petroleum products. Use of diolefins for chemical syntheses and the like is frequently facilitated by having these materials substantially pure and free of other types of hydrocarbons. In general, the five- and six-carbon-atom diolefins have boiling points quite near the boiling points of hydrocarbons of other types containing the same number of carbon atoms. For instance, the range of boiling points of five-carbon-atom hydrocarbons is from about 50° F. to higher than 125° F. and more than forty hydrocarbons are known to boil within this range, which includes the boiling points of the five-carbon-atom diolefins, or pentadienes, such as isoprene and piperylene. In the case of isoprene, boiling at 93.3° F., there are olefins containing five carbon atoms which boil below isoprene at temperatures of 86 and 87.8–88° F. and others boiling above isoprene at about 96.6 and 98–99° F.; normal pentane, boiling at about 96.9° F. is still another hydrocarbon which has a boiling point quite near to that of isoprene. In the case of the six-carbon atom diolefins, such as hexadiene-1,3, 2,3-dimethyl butadiene-1,3, etc., the number of like-boiling non-diolefinic hydrocarbons is even greater.

Hydrocarbon mixtures produced by cracking or other operations which contain five- or six-carbon-atom diolefins will in general contain a substantial number of hydrocarbons of other types, at least some of which will have boiling points quite close to the boiling points of the diolefins. Under such circumstances, it is difficult, and sometimes impossible, to separate in good purity the individual diolefins by conventional fractional distillation.

Accordingly, it is an object of this invention to provide a process for the concentration of five- and six-carbon-atom diolefins from hydrocarbon mixtures containing the same. Another object is to provide a specific entraining agent, methyl formate, for use in the distillation of such diolefin-containing mixtures. A further object is to provide a method for the separation by azeotropic distillation with methyl formate of

hydrocarbons of the classes of paraffins, mono-olefins, and naphthenes, having boiling points close to that of a five- or six-carbon diolefin so as to concentrate or isolate a substantially pure diolefin from a complex hydrocarbon mixture. Other objects and advantages will be ascertained from the following detailed disclosure.

The accompanying drawing, which is self-explanatory, portrays diagrammatically the process of the present invention.

My invention is a process for the separation of diolefins having five or six carbon atoms to the molecule from other types of hydrocarbons such as paraffins, olefins and naphthenes, by fractionally distilling mixtures containing these types of hydrocarbons in the presence of a highly selective entrainer, methyl formate, which forms minimum-boiling azeotropic mixtures with individual hydrocarbons in the mixture. I usually prefer to apply this process to hydrocarbon mixtures of relatively narrow boiling range, such as may be obtained by a preliminary fractionation, which would normally contain one or more diolefins together with close-boiling hydrocarbons of other types. Such hydrocarbon mixtures should not generally contain more than minor amounts of olefinic, paraffinic, or cyclic compounds having boiling points more than about say 6° F. higher than the boiling point of the diolefin contained in the fraction, although in some cases non-diolefinic hydrocarbons boiling considerably higher than the desired diolefin may be separated by my process. While methyl formate has the effect of widening the spread between distillation temperatures of low-boiling or like-boiling impurities and the diolefin, the reverse may tend to be true in the case of impurities which boil much higher than the diolefin. Thus the azeotrope of a high-boiling hydrocarbon may not be sufficiently volatile to allow its separation overhead from the diolefin. Accordingly, non-diolefinic hydrocarbons which boil considerably above the diolefin are ordinarily better separated by conventional fractionation previous to the distillation in the presence of methyl formate. However it should be noted that the selectivity of methyl formate as between diolefins and non-diolefins is so much greater than other generally known entraining agents that the limitation as to the high-boiling impurities just discussed is not nearly so critical as might be expected, and non-diolefins are frequently taken off overhead ahead of the diolefin by distillation with methyl formate even though their boiling points are as much as 10 to 15° F. higher than that of the diolefin which is to be purified. The extent to which this may be done will depend upon the types and boiling range of the non-diolefinic hydrocarbons involved. No such limitation as the above applies to undesired

hydrocarbons boiling below the particular diolefin in question; a rather wide range of boiling points below that of the diolefin is permissible.

A specific example of my process which illustrates its superiority over ordinary distillation is as follows:

EXAMPLE

A mixture of isoprene and close-boiling impurities, mainly 2-methyl-1-butene and pentene-2, having a refractive index (n_D^{20}) of 1.4100 and an estimated isoprene content of 68 to 73 per cent, was subjected to ordinary batch-wise fractionation in a column of 1.2 cm. inside diameter packed to a height of 90 cm. with $\frac{1}{8}$ inch diameter single-turn wire helices. The course of the distillation is shown in Table I.

TABLE I
Conventional fractionation of an isoprene concentrate

Fraction	Boiling range (corrected to 760 mm. Hg), °F.	Reflux ratio	Vol. per cent of charge	Cumulative vol. per cent of charge	Olefin assumed present for purity calculations	n_D^{20}	Per cent isoprene in fraction (by n_D^{20})
1	84.6-91.6	15:1	14	14	2-methyl-1-butene	1.4021	-----
2	89.8-90.7	15:1	13	27	do	1.4069	66
3	90.7-92.7	15:1	18	45	do	1.4106	75
4	91.1-92.3	30:1	11	56	do	1.4161	87
5	91.4-92.3	80:1	6	62	do	1.4177	11
6	91.1-93.2	60:1	5	67	do	1.4178	91
7	92.9-93.2	40:1	12	79	do	1.4175	90
8	93.1-93.9	40:1	12	91	Pentene-2	1.4140	82
Kettle residue + losses			9	100			

Estimates of the purity of the various fractions are based upon the known refractive indices for isoprene and the olefins. It is seen that in this fractionation about nine per cent impurities were present in the best isoprene fractions.

A second fractionation was then conducted in the same column but in the presence of methyl formate as an entraining agent. The hydrocarbon mixture contained about 71 per cent isoprene and 2-methyl-1-butene comprised the bulk of the impurity. The refractive index (n_D^{20}) of the hydrocarbon mixture was 1.4090. The liquid volume ratio of methyl formate to hydrocarbon in the charge to the column was 1.35 to 1. The results of the fractionation are shown in Table II.

far more efficient separation of impurities than was accomplished by conventional fractionation. The efficacy of my process, as embodied in this example, is self-evident.

While I have shown by way of example the separation of isoprene in substantially pure form from admixture with close-boiling non-diolefinic hydrocarbons, I have found that by the use of methyl formate in accordance with this invention, I may also readily effect the purification of other 5- and 6-carbon-atom diolefins from complex hydrocarbon mixtures. For example, I have discovered that separation of low- and/or high-boiling piperylene from a mixture which also contains the close-boiling unsaturated alicyclic hydrocarbon cyclopentene, to be impossible by even the most efficient conventional fractionation

because of the formation of constant-boiling mixtures of cyclopentene with each of the geometrical isomers of piperylene. This constant-boiling mixture contains about 9 volume per cent of cyclopentene in the case of the low-boiling piperylene, and about 50 volume per cent of cyclopentene in the case of the high-boiling piperylene. Since cyclopentene is usually present in admixture with the piperylenes, and since its presence in piperylene may frequently affect greatly the polymerization properties and the characteristics of a finished product of piperylene, it is highly important to find some simple method of resolving the afore-mentioned constant-boiling mixtures. I have found that this may be done by fractionation in the presence of

TABLE II
Fractionation of an isoprene concentrate with methyl formate

Fraction	Boiling range (corrected to 760 mm. Hg), °F.	Reflux ratio	Volume per cent of charge	Cumul. vol. per cent of charge	Vol. per cent methyl formate in overhead	Olefin assumed present for purity calculations	n_D^{20}	Per cent isoprene in fraction (by n_D^{20})
1	73.1-76.7	50:1	16	16	40.7	2-methyl-1-butene	1.3784	<5

Loss in distillation and washing samples			18	100				

The amounts, refractive indices, and estimated purities of the various fractions refer to the hydrocarbons recovered after removing methyl formate by water washing.

It will be noted that the use of methyl formate as an entrainer resulted in production of isoprene of 97 to 100 per cent purity, which represents a

70 methyl formate to separate out cyclopentene from the piperylene if such a constant-boiling mixture is used as hydrocarbon feed to the column. This offers a convenient means of concentrating piperylene to any desired extent.

I generally prefer to carry out my process at temperatures varying from about 70° F. to about

120° F. and at pressures from about atmospheric to pressures of about two atmospheres, absolute. It is usually convenient to operate at or slightly above atmospheric pressure. If desired, lower or higher temperatures and pressures may be used.

It is desirable to operate my process at as low a temperature in the kettle and throughout the column as is convenient; methyl formate has some tendency toward decomposition or degradation when heated and this tendency may be minimized by keeping the temperature at a low level.

While my process has been discussed with particular reference to batch-wise fractional distillations, my process is equally applicable to continuous fractionation, in which case the hydrocarbon mixture is continuously charged to the fractionating column at some point along the column and the entrainer may be added at the same point or some other point or points along the column. In such a continuous fractionation the diolefin ordinarily is removed from the kettle of the column and azeotropic mixtures of methyl formate with the other hydrocarbons present are taken off the top of the column. The diolefin removed from the column kettle may or may not contain substantial amounts of the entrainer, depending upon the relative amounts of entrainer and hydrocarbon mixture charged to the column, and my process may be operated with any desired ratio of entrainer to hydrocarbon mixture equal to or greater than a minimum ratio which will be determined by the amount of entrainer required to form azeotropic mixtures with the hydrocarbons which are to be distilled away from the diolefin. The many different ways of carrying out azeotropic distillations which are known to the art may be applied with suitable modification to carry out the present invention.

In operating my process, I use any convenient method of removing the entrainer from the products of the fractionation, such as water washing. If the diolefin is removed as a kettle product it may contain any high-boiling materials resulting from decomposition or degradation of a part of the methyl formate. Such high-boiling materials may not always be water-soluble and hence would not be removed by water washing of the kettle product as the entrainer is. In such a case it is occasionally necessary first to water-wash the kettle product to remove all water-soluble material, and then to free the diolefin product of high boiling materials by distilling the diolefin overhead in auxiliary equipment.

Since the invention may be practiced otherwise than as specifically described herein, and since many modifications and variations of it will be obvious to those skilled in the art, it should not be restricted except as specified in the appended claims.

I claim:

1. The process of effecting separation of substantially pure piperylene from admixture with 10 cyclopentene which comprises fractionally distilling the mixture of piperylene and cyclopentene in the presence of methyl formate in amount sufficient to form an azeotropic mixture with all of said cyclopentene and thereby effecting substantially complete separation of said cyclopentene from said piperylene, said cyclopentene being recovered overhead in the form of an azeotrope with said methyl formate.

2. The process of effecting separation of piperylene from admixture with close-boiling C₅ hydrocarbons including a substantial proportion of cyclopentene which comprises fractionally distilling the mixture of piperylene and said C₅ hydrocarbons in the presence of methyl formate in 25 amount sufficient to form an azeotropic mixture with all of said C₅ hydrocarbons and removing said azeotropic mixture of methyl formate with said C₅ hydrocarbons overhead while leaving said piperylene behind.

3. The process of effecting separation of piperylene from admixture with close-boiling pentenes including a substantial proportion of cyclopentene which comprises fractionally distilling the mixture of piperylene and said pentenes in the presence of methyl formate in amount sufficient to form an azeotropic mixture with all of said pentenes and removing said azeotropic mixture of methyl formate with said pentenes overhead while leaving said piperylene behind.

4. The process of effecting the resolution of a constant-boiling mixture of piperylene and cyclopentene into piperylene and cyclopentene fractions which comprises fractionally distilling said constant-boiling mixture of piperylene and cyclopentene in the presence of methyl formate in amount sufficient to form an azeotropic mixture with all of said cyclopentene and removing said azeotropic mixture of methyl formate with cyclopentene overhead while leaving said piperylene 50 behind.

CHARLES E. WELLING.
